W. F. HARRINGTON

COMBINED LOCK AND LATCH FOR DOORS

Filed Dec. 29, 1923

INVENTOR.
William F. Harrington.
BY Solon J. Brightton
ATTORNEY.

UNITED STATES PATENT OFFICE.

WILLIAM F. HARRINGTON, OF TOLEDO, OHIO.

COMBINED LOCK AND LATCH FOR DOORS.

Application filed December 29, 1923. Serial No. 683,282.

To all whom it may concern:

Be it known that I, WILLIAM F. HARRINGTON, a citizen of the United States, residing at Toledo, in the county of Lucas and 5 State of Ohio, have invented certain new and useful Improvements in Combined Locks and Latches for Doors, of which I declare the following to be a full, clear, and exact description.

10 This invention relates to combined locks and latches for doors, particularly vehicle doors, and embodies improvements upon the structure set forth in my co-pending application, Serial Number 617,437, filed February 15 ary 7th, 1923.

One object of the invention is the provision of means adapted to be operated from inside the door for preventing the actuation of the latch bolt, by preventing the turning 20 of the outside door handle.

Another object is the location of the aforesaid means upon the oscillatable rod used for actuation of the latch bolt from the inside of the door, thus avoiding the cutting 25 of the upholstery, and removing the said means to a more accessible position.

Still another object is the provision of automatically operating means for releasably holding the aforesaid means in both its operative and inoperative positions.

Other objects, and objects relating to details of construction and economies of manufacture, will appear as I proceed with the description of that embodiment of the invention which, for the purposes of the present application, I have illustrated in the accompanying drawings, in which:

Figure I is a side elevation of a combined latch and lock for vehicle doors, showing 40 the side of the lock which faces the interior of the vehicle.

Fig. II is a vertical, sectional, detail view taken substantially on the line II—II, Fig. I.

Fig. III is a horizontal, sectional, detail view taken substantially on the line III—III, Fig. I.

Fig. IV is a horizontal, sectional, view taken on the line IV—IV, Fig. I, showing a spring washer which may be employed.

50 Fig. V is an elevational view of the sleeve showing the spiral slot therein.

Fig. VI is a view taken substantially at right angles to Fig. V. and showing the upper portion of the sleeve and its operating 55 disc in section, and

Fig. VII is a central, vertical, sectional view of the upper end of the oscillatable rod with the sleeve in place thereon.

Similar reference characters refer to like parts throughout the views.

In the drawings, 10 represents the main casing plate or base plate. At one vertical edge it is bent at a suitable angle to form the front or face plate 11, in which is formed an opening in order that the latch bolt 12 60 may protrude therethrough. The latter slides upon the surface of the plate 10, being guided by the walls of the opening in the face plate 11 and between lips 13 struck up out of the base plate 10. At the rear end 65 of the bolt, there is an offset portion 14, which slides in upper and lower tracks 15. These tracks are bent up out of a smaller casing plate 16, which is fastened to the plate 10 by suitable means, as by tongues 17 70 set into slots in the face plate 11, and screws 18 extending through spacers (not shown), and threaded into holes in the base plate 10.

19 is a roll-back adapted to be actuated by an outside door knob (not shown), and arranged to engage one of two wings 20 which are integral with the latch bolt 12 and extend therefrom in opposite directions between the two plates. Symmetrically arranged with respect to roll-back 19, but 80 upon the opposite side of the latch bolt, is a locking dog 21, intended to be operated by a key from the outside of the door and arranged to engage behind a shoulder on the latch bolt to prevent its being retracted. 90 The journals for the roll-back 19, and locking dog 21, are of the same size and may be interchanged for right and left hand opening doors. The locking dog 21 may be omitted in some cases, and in fact, it is used 95 ordinarily upon one door only of each vehicle.

The latch bolt 12 is normally urged toward latching position by a coil spring 22, the free end of the spring bearing upon a 100 rounded surface 23 of the bolt.

A groove or trough 24 is formed in the plate 10, open towards the plate 16, and running at right angles to the bolt 12. This trough extends entirely through the plate 10 from one edge to the other, as appears more in detail in my co-pending application above referred to. In the trough are laid 105 a pair of bushings 25, which are held against movement longitudinally of the trough, by 110

projections upon the cover plate 16, as is also clearly shown in my previous application. Within these bushings is journaled a rod 26 carrying intermediate its length a 5 crank arm 27, which extends into an elongated opening in the offset portion 14 of the latch bolt and has a bearing against the bolt at the rear of the opening, whereby rotation of the rod 26 retracts the bolt against the 10 action of spring 22.

A small spring washer 28 is slipped over the rod 26 into contact with the upper one of the two bushings 25. This washer has two ears 29 which rest against the plate 15 10 at the sides of the groove or trough 24, and thus prevent the rotation of the washer. Above the washer 28 and resting upon the upper surface of the latter, is a sleeve 30 having at its upper end, some means for 20 turning the same; such for instance, as a disc 31 with a downturned knurled edge. In the lower end of the sleeve there are two diametrically arranged notches 32, which co-operate with projections 33 on the washer. 25 A handle 34 having a squared opening therein, is mounted upon the squared upper end of the rod 26, being held on with a screw 35, as shown in Fig. VII. Interposed between the handle 34 and the disc 31, is a 30 spring washer 36, considerably more effective than the washer 28, and tending to hold the sleeve and washer 28 in close contact so that the co-operating notches and projections will retain the sleeve releasably in either one of two positions 180° apart. The upper spring washer 36 is not necessary where the proportions and adjustment of the parts are absolutely correct, but it is 35 highly desirable in practice, because of manufacturing variations, and as rendering fine adjustment unnecessary.

Near its lower extremity, the sleeve 30 is provided with a spiral slot 37 extending approximately half-way around the circumference of the sleeve. This spiral slot is 45 adapted to receive a projection, such as a pin 38 on one end of a lever 39, the latter being pivoted upon a pin 40, which may be mounted in a hole in the plate 10. In practice, I form the plate 10 with two such holes 41, so that the same parts may be utilized for right and left hand doors. The end of the lever 39 which is opposite the end 38, is 50 shaped to fit in front of a shoulder on the roll-back 19 to prevent that element from moving in response to a rotational effort put upon the outside door handle. It will be obvious that rotation of the sleeve 30 for 55 180° in an anti-clockwise direction from the position shown in Fig. I, will cause the spiral slot 37 to lift the adjacent end of lever 39 and depress the opposite end to lock the roll-back 19. Rotation of the sleeve in the opposite direction will withdraw the lever 39 from engagement with

the roll-back and permit the opening of the door from the outside. In either position, the sleeve 30 and the lever 39 are held against accidental movement by the spring washer 28.

While I have shown and described in considerable detail, a specific embodiment of my invention, it is to be understood that the present showing and description are illustrative only, and that I do not regard the 70 invention as limited to the details of construction illustrated and described, nor any of them, except in so far as I have included such limitations within the terms of the following claims, in which it is my intention 75 to claim all novelty inherent in my invention broadly, as well as specifically.

I claim as my invention:

1. In a lock for vehicle doors, a slidable latch bolt, a spring for throwing said bolt to operative position, means for retracting said bolt, a second means for retracting the bolt including an oscillatable rod, and means for preventing the operation of said first-named means, including a sleeve surrounding said rod and rotatable thereon, a pivoted locking lever and an operative connection between said sleeve and lever.

2. In a lock for vehicle doors, a slidable latch bolt, a spring for throwing said bolt to operative position, an outside door handle for retracting said bolt, a second means for retracting the bolt including an oscillatable rod, a sleeve surrounding said rod, and means including a pivoted lever adapted to be operated by the rotation of said sleeve for preventing the actuation of said door handle.

3. In a lock for vehicle doors, a slidable latch bolt, a spring for throwing said bolt to operative position, means for retracting said bolt, a second means for retracting the bolt including an oscillatable rod, means for preventing the operation of said first-named means including a sleeve surrounding said rod and rotatable thereon, and automatically acting means for releasably holding said sleeve in operative or inoperative position.

4. In a lock for vehicle doors, a slidable latch bolt, a spring for throwing said bolt into operative position, an oscillatable rod, connections between said rod and bolt for retracting the latter, a sleeve surrounding said rod and rotatable thereon, a spiral cam on said sleeve, and a pivoted locking lever having a projection arranged to co-operate with said cam for the actuation of said lever.

5. In a lock for vehicle doors, a casing plate formed with a trough therein, an oscillatable latch operating rod mounted within said trough, a sleeve surrounding said rod and rotatable thereon; a locking lever pivoted upon said casing plate, a spiral cam actuator on said sleeve engaging said lever,

and a washer surrounding said rod adjacent the lower end of said sleeve and provided with projections adapted to engage said casing plate adjacent to the trough, said sleeve and washer having a complementary projection and socket for releasably holding the sleeve in a predetermined position.

5 6. In a lock, a rotatable rod, a sleeve surrounding said rod and rotatable with respect thereto, locking means operatively connected with said sleeve, and a detent for said sleeve comprising a spring washer also surrounding the rod, said sleeve and detent being provided with complementary projections and notches, and means for preventing the rotation of said washer.

10 7. In a lock for vehicle doors, a casing plate formed with a trough therein, an oscillatable latch operating rod mounted within said trough, means for locking said latch, a sleeve surrounding the said rod and rotatable thereon to actuate said locking

means, a washer surrounding said rod adjacent one end of said sleeve, and interengaging means between said casing plate and washer to prevent rotation of the latter, said sleeve and washer having a complementary projection and socket for releasably holding the sleeve in a predetermined position.

15 8. In a lock for vehicle doors, a slidable latch bolt, a spring for throwing said bolt to operative position, means for retracting said bolt, a further means for retracting said bolt including a vertical oscillatable crank, means for preventing the operation of said first-named retracting means including an element mounted to oscillate about the axis of oscillation of said crank, a pivoted locking lever, and an operative connection between said lever and said element.

20 In testimony whereof, I affix my signature.

WILLIAM F. HARRINGTON.
